FLUID COOLING APPARATUS

Matthew M. Lawler, Short Hills, and Paul F. Bahler, Haworth, N. J., assignors to Washington Pump and Machinery Corporation, Harrison, N. J., a corporation of Delaware

Application July 1, 1943, Serial No. 493,120

9 Claims. (Cl. 62—115)

1

This invention relates to a cooling or refrigeration system or apparatus, and more particularly to such an apparatus adaptable for use in a system for catalytic alkylating of hydrocarbons, in which a condensing catalyst is employed to promote the reaction between the iso-paraffinic and the olefinic hydrocarbons employed as the feed stock to produce an alkylated iso-paraffinic hydrocarbon suitable for use in an aviation motor fuel.

In carrying out the process of catalytic alkylating of hydrocarbons wherein iso-paraffinic hydrocarbons, such as iso-butane, iso-pentane and the like are reacted with olefinic hydrocarbons in the presence of a catalyst such as sulfuric acid, the reaction which takes place is exothermic, and experience has shown that the reaction should be conducted at a temperature of from 30° F. to 50° F. in order that polymerization losses be held to a minimum. Such a process, therefore, requires the use of mechanical refrigeration to remove the heat generated by the reaction and to maintain the temperature of the acid hydrocarbon emulsion at the desired degree.

In carrying out such a process it has also been found desirable to provide means for circulating an excess of iso-paraffinic to olefine and to obtain a high rate of flow of the hydrocarbon acid emulsion to promote thorough mixing, and also to facilitate cooling.

An object of the present invention is to provide a mechanical refrigeration apparatus which will bring about a high degree of heat transfer rate between the hydrocarbon emulsion and the refrigerant to maintain the temperature of the acid hydrocarbon emulsion at the desired degree, and provide a high rate of flow of the emulsion, which apparatus is simple in construction and of low initial and operating cost in comparison with approved equipment now employed for the same or analogous purposes.

Another object of the present invention is the provision of a refrigerating or cooling apparatus which is compact, provides ease and simplicity of control, and reduces friction losses of refrigerant flow to a minimum thereby reducing the power consumption of the unit to maintain a pre-determined heat transfer relation between the cooling or refrigerating agent and the fluid to be cooled.

With these and other objects in view, as may appear from the accompanying specification, the invention consists of various features of construction and combination of parts, which will be first described in connection with the accompanying drawings, showing a refrigeration or cooling sys-

2

tem of a preferred form embodying the invention, and the features forming the invention will be specifically pointed out in the claims.

In the drawings:

5 Figure 1 is a diagrammatic view showing the improved cooling or refrigerating apparatus in a system for catalytic alkylating of hydrocarbons.

10 Figure 2 is a cross-section through the reactor or evaporator employed in the system showing its connections and relation with the other elements of the refrigerating or cooling system.

15 Figure 3 is a longitudinal section through the reactor.

In the process of catalytic alkylating of hydrocarbons, in which a condensing catalyst is employed to promote the reaction between the iso-paraffine and the olefinic hydrocarbon which is employed as the feed stock to produce an alkylated iso-paraffinic hydrocarbon suitable for use in an

20 aviation motor fluid, the fresh hydrocarbon is fed through a suitable inlet or feeding means 1 into the inlet space 2 of the combined mixing and inlet chamber 3 formed at one end of the shell 4 of the reactor 5 by the tube head 6. The

25 catalyst or acid, such as sulphuric acid is delivered to the inlet space 2 of the combined inlet and mixing chamber 3 through a suitable inlet pipe 7. The combined inlet and mixing chamber 3 has a conical partition 8 therein which divides

30 the chamber into the inlet space 2 and the circulating space 9. The partition 8 is provided with an opening 10 which establishes communication between the inlet space 2 and the circulation space 9. A combined pumping and mixing impeller 11 is positioned in the opening 10 and it may be rotated by any suitable type of prime mover such as an electrical motor shown at 12.

35 The fresh hydrocarbon which is projected towards the impeller 11 by a nozzle 14 is partially mixed with the acid catalyst in the space 2, and it is more thoroughly mixed by the action of the impeller 11 which draws the hydrocarbon and catalyst from the space 2 and discharges it into the circulating space 9. From the circulating

40 space 9 in the reactor 5 the mixture or emulsion of the hydrocarbon and catalyst flows through a plurality of relatively large tubes 15 into the combined return and outlet chamber 16 of the reactor. The combined return and outlet chamber

45 16 is formed by the tube head 17 and the head 18 of the shell 4. The tube heads 6 and 17 which support the tubes 15 form the cooling or evaporating chamber 18 between a combined inlet and mixing chamber 3 and the combined outlet

50 16. The tube heads 6 and 17 which support the tubes 15 form the cooling or evaporating chamber 18 between a combined inlet and mixing chamber 3 and the combined outlet

55 and return chamber 16.

The tubes 15 are arranged in an annular set as clearly shown in Figure 2 of the drawings, and a plurality of smaller return tubes 19 extend through the cooling or evaporating chamber 18 and establish communication between the return chamber 16 and the inlet space 2 of the combined inlet and mixing chamber 3 so that the emulsion or mixture of hydrocarbon and acid catalyst flows from the circulating space 9 through the tubes 15 into the return chamber 10 15 and part of it returns through the tubes 19 to the inlet space 2 where it is mixed with the incoming fresh hydrocarbon and acid catalyst and recirculated.

Part of the alkylate passes from the combined outlet and return chamber 16 through the outlet 20 to the separator 21 where the acid catalyst is separated out from the hydrocarbon and either passes to a point of suitable disposition through the outlet 22 or is returned to the reactor through the by-pass connection 23 between the separator 21 and the inlet pipe 7 for the fresh acid catalyst. The hydrocarbon is drawn off through a suitable outlet 24 to the fractionator.

As hereinbefore pointed out in a process of this type for producing an alkylated iso-paraffinic hydrocarbon suitable for use in an aviation motor fuel, the reaction which takes place is exothermic and the best results, so as to reduce polymerization losses to a minimum, is provided when the reaction is conducted at a temperature of from 30° F. to 50° F.; therefore, refrigeration mechanism is provided in combination with the reactor to provide for the cooling or refrigerating of the emulsion of hydrocarbon and acid catalyst during its circulation through the reactor 5.

A closed refrigeration system embodying the reactor is shown in Figures 1 and 2 of the drawings and it embodies a centrifugal compressor 25 which may be of the type of compressor shown 40 in U. S. Patent No. 2,286,522 or any other approved type of centrifugal compressor.

The suction of the centrifugal compressor 25 is connected through a suitable connection 26 with a passage 27 formed in the shell 4 of the reactor 5. The passage 27 has its inlet opening into the top of the cooling or evaporation chamber within the reactor 5 so that the liquid refrigerant which is evaporated therein during the cooling of the emulsion passes upwardly about a part of the tubes 15 and into the passageway 27 from which it enters the suction of the centrifugal compressor 25 where it is compressed. The centrifugal compressor 25 delivers the compressed vaporized refrigerant to a condenser 28 55 of any approved construction which may be purchased upon the open market. The compressed vaporized refrigerant is condensed in the condenser 28, and the condensed liquid refrigerant passes from the condenser 28 through the suitable connection 29 into the cooling or evaporation chamber 18 of the reactor 5. As shown in Figure 2 of the drawings, the return tubes 19 are arranged in upper and lower nests within a trough 30 so as to insure that the return tubes 19 will be at all times submerged in liquid refrigerant. The liquid refrigerant overflows from the trough 29 into the lower part of the shell 4 and submerges the return tubes 19 in the lower nest. The reactor 5 with its construction as heretofore described embodying the impeller 11 will provide the greatest possible velocity of the emulsion through the tubes 15 and 19 with a minimum capacity of the circulating pump or the impeller 11

5 since it is known that heat transfer rates increase with increased velocity of the liquid to be cooled over the cooling surface, the arrangement whereby the liquid to be cooled is circulated through the tubes which are immersed in the liquid refrigerant will provide a high degree of cooling with a structure of minimum size.

10 The employment of the centrifugal compressor in the system has numerous advantages among which are the compactness of the refrigerating unit, the ease and simplicity of control of the unit and consequently of control of the cooling by control of the refrigerant delivered to the reactor, and further it provides a very material reduction in friction loss of refrigerant flow over the frictional losses which are caused by the use of reciprocating compressors. A friction loss in the refrigerant flow represents heat transfer loss and increased horse power to maintain a predetermined heat transfer and consequently the use of the centrifugal compressor reduces the power consumption of the system. Further, there is a marked advantage in the initial cost of a unit employing a centrifugal compressor in lieu of one employing a reciprocating compressor, and also the use of the centrifugal compressor permits an individual refrigerating unit for each reactor in an alkylating plant, which is an economical feature and also provides a better unitary control in a battery of reactors, in that, in lieu of throttling refrigerant flow as would be required by the employment of a single reciprocating compressor for a battery of reactors, control of the compressor is provided to compensate for varying conditions in the reactor.

15 The centrifugal compressor 25 is shown in Figure 1 of the drawings as being driven by a steam turbine 35, but it is to be understood that it may be driven by any suitable type of prime mover without departing from the spirit of the present invention.

20 With the steam turbine drive for the centrifugal compressor 25, a diagrammatic Figure 1 of the drawings shows a temperature control, for controlling the temperature of the emulsion in the reactor by controlling the speed of operation of the turbine 35 and consequently controlling the speed of operation of the centrifugal compressor 25 and the quantity of refrigerant delivered to the reactor.

25 A thermal bulb 36 of any approved type is inserted into the return and outlet chamber 16 and it is connected to a temperature cut-off switch 37 of any approved construction which may be purchased upon the open market. The temperature cut-off switch 37 controls the energizing of the solenoid 38 of a conventional type of three-way valve 39. The three-way valve 39 is positioned in a supply line 40 for air under pressure, and either delivers air under pressure to the pressure actuated regulating valve structure 41 or permits air under pressure to bleed from the pressure actuated regulating valve 41 depending upon the operation of the solenoid 38. The pressure actuated valve 41 is connected in the steam line 42 to the turbine 35 so that by controlling operation of the valve 41 the quantity of steam delivered to the turbine 35 is controlled for controlling the speed of operation of the turbine.

30 This is only one type of control which may be employed for controlling the quantity of refrigerant delivered to the reactor, and it is to be understood that any approved type of control mechanism for use either with a steam turbine

or an electric motor may be provided without departing from the spirit of the present invention.

It will be understood that the invention is not to be limited to the specific construction or arrangement of parts shown, but that they may be widely modified within the invention defined by the claims.

What is claimed is:

1. In a refrigerating or cooling system for use in the catalytic alkylation of hydrocarbons, the combination, of a reactor comprising a shell, tube heads in said shell providing an inlet chamber, a combined return and outlet chamber and an intermediate cooling chamber, a partition in said inlet chamber forming a circulating space, a set of tubes extending through said cooling chamber and opening into the circulating space and said combined return and outlet chamber, a second set of tubes extending through said cooling chamber and opening into the inlet chamber and the return and outlet chamber, means for delivering a liquid refrigerant into said cooling chamber for contact with the second set of tubes, said cooling chamber having an outlet for vaporized refrigerant, a part of said first set of tubes being arranged in said shell so as to be free from contact with liquid refrigerant but being located in the path of vaporized refrigerant to said outlet.

2. In a refrigerating or cooling system for use in the catalytic alkylation of hydrocarbons, the combination, of a reactor comprising a shell, tube heads in said shell providing an inlet chamber, a combined return and outlet chamber and an intermediate cooling chamber, a partition in said inlet chamber forming a circulating space, a set of tubes extending through said cooling chamber and opening into the circulating chamber and said combined return and outlet chamber, a second set of tubes extending through said cooling chamber and opening into the inlet chamber and the return and outlet chamber, means for delivering a liquid refrigerant into said cooling chamber for contact with the second set of tubes, said cooling chamber having an outlet for vaporized refrigerant, a part of said first set of tubes being arranged in said shell so as to be free from contact with liquid refrigerant but being located in the path of vaporized refrigerant to said outlet, independent spaced inlet means for admitting respectively a catalyst and fresh hydrocarbon to said combined inlet and mixing chamber whereby mixed catalyst and hydrocarbon entering the combined mixing and inlet chamber from said second set of tubes will be mixed with incoming catalyst and fresh hydrocarbon.

3. In a refrigerating or cooling system for use in the catalytic alkylation of hydrocarbons, of a reactor comprising a shell, tube heads in said shell providing a combined mixing and inlet chamber, a combined return and outlet chamber and an intermediate cooling chamber, independent spaced inlet means opening into said combined mixing and inlet chamber for admitting respectively a catalyst and fresh hydrocarbons to the combined inlet and mixing chamber, a plurality of tubes connecting said inlet and return chambers and extending through said cooling chamber, a partition in said combined mixing and inlet chamber dividing it into an inlet space and a circulating space, said partition provided with an opening establishing communication between said inlet space and said circulation space, said tubes which communicate with said return and outlet chamber and said inlet and mixing

10

chamber serving to return mixed catalyst and hydrocarbon to the inlet chamber for mixing with incoming catalyst and fresh hydrocarbon, a combined mixing and pumping impeller in said opening to facilitate mixing and to circulate said mixed catalyst and hydrocarbon, said cooling chamber having an inlet for refrigerant located so as to immerse part of the tubes connecting the combined outlet and return chamber and the combined inlet and mixing chamber with liquid refrigerant, and means for circulating refrigerant through said cooling chamber.

4. A refrigerating or cooling system as claimed in claim 1 which includes means associated with some selected tubes of the second set of tubes to retain liquid refrigerant to cause immersion of said selected tubes in liquid refrigerant.

5. In a refrigerating or cooling system as claimed in claim 2 wherein the tubes of said first set of tubes have a greater cross sectional area than the tubes of the second set of tubes whereby a greater quantity of liquid will be delivered to said return chamber from said mixing space than will be returned from the return chamber to the inlet space.

25

6. In a refrigerating or cooling system for use in the catalytic alkylation of hydrocarbons, a reactor comprising a shell, tube heads in said shell providing an inlet chamber, a combined return and outlet chamber and an intermediate cooling chamber, a partition in said inlet chamber forming a circulating space, a set of tubes extending through said cooling chamber and opening into the circulating chamber and said combined return and outlet chamber, a second set of tubes extending through said cooling chamber and opening into the inlet chamber and the return and outlet chamber, means for delivering a liquid refrigerant into said cooling chamber for contact with said second set of tubes, said cooling chamber having an outlet for vaporized refrigerant, a trough enclosing a part of said second set of tubes, said liquid refrigerant delivering means located to deliver liquid refrigerant into said trough to immerse the tubes enclosed in the trough in liquid refrigerant.

30

7. In a refrigerating or cooling system for use in the catalytic alkylation of hydrocarbons, a reactor comprising a shell, tube heads in said shell providing an inlet chamber, a combined return and outlet chamber and an intermediate cooling chamber, a partition in said inlet chamber forming a recirculating space, a set of tubes extending through said cooling chamber and opening into the circulating chamber and said combined return and outlet chamber, a second set of tubes extending through said cooling chamber and opening into the inlet chamber and the return and outlet chamber, means for delivering a liquid refrigerant into said cooling chamber for contact with said second set of tubes, said cooling chamber having an outlet for vaporized refrigerant, a trough enclosing a part of said second set of tubes, said liquid refrigerant-delivering means located to deliver liquid refrigerant into said trough to immerse the tubes enclosed in the trough in liquid refrigerant, the tubes of said first set of tubes having a greater cross-sectional area than the tubes of the second set of tubes whereby a greater quantity of liquid will be delivered to said return chamber from said mixing space than will be returned from the return chamber to the inlet space.

70

8. In a refrigerating or cooling system for use in the catalytic alkylation of hydrocarbons, a re-

actor comprising a shell, tube heads in said shell providing an inlet chamber, a combined return and outlet chamber and an intermediate cooling chamber, a partition in said inlet chamber forming a circulating space, a set of tubes extending through said cooling chamber and opening into the circulating chamber and said combined return and outlet chamber, a second set of tubes extending through said cooling chamber and opening into the inlet chamber and the return and outlet chamber, means for delivering a liquid refrigerant into said cooling chamber for contact with said second set of tubes, said cooling chamber having an outlet for vaporized refrigerant, a trough enclosing a part of said second set of tubes, said liquid refrigerant-delivering means located to deliver liquid refrigerant into said trough to immerse the tubes enclosed in the trough in liquid refrigerant, the part of said second set of tubes which is not enclosed in said trough being located beneath the trough whereby liquid refrigerant spilling out of the trough will contact them.

9. In a refrigerating or cooling system as claimed in claim 1 wherein the tubes of the first set of tubes other than those located in the path

of the vaporized refrigerant flow to the outlet are located in the bottom of the shell whereby they will be contacted by liquid refrigerant, and wherein the cross-sectional areas of the tubes in the path of the vaporized refrigerant is greater than the sum of the cross-sectional area of the tubes located in the bottom of the shell.
